S. S. Denney

ATTORNEY.

UNITED STATES PATENT OFFICE

WILLIAM T. DEMPSEY, OF PHILADELPHIA, PENNSYLVANIA

BOOKMARK

Application filed March 31, 1932. Serial No. 602,181.

My invention is an improved bookmark and a container housing the same for display, demonstration and shipment, and a leading object of my invention is the provision of a bookmark which may be inserted in a book in a manner giving the appearance and effect of a bookmark bound into the book, which is readily detachable for insertion in another book, but when inserted, is securely held against accidental displacement.

A further object of my invention is the provision of means facilitating the merchandising of my improved bookmark, and presenting to the eye of a prospective purchaser the mode of operation and use thereof without the necessity of verbose description. Such merchandising means further provides means to protect the ribbon forming a part of the marker against tearing, fraying, massing or soiling.

In its preferred form, my invention consists of a detachable bookmark comprising a flexible finder, such as a ribbon, for insertion between the book leaves, and a setaceous retaining member housed by the bookbinding and forming an anchorage for an end of the finder fixed to the body of the retaining member. The retaining member may be conveniently formed from a folded strip lapped over resilient filaments, such as horse-hair, which project far enough from the sides of the folded strip to be bent by insertion into housed position in the binding and yieldingly resist removal therefrom. The ribbon may also have an end housed between the laminations of the finder which are secured together by a suitable adhesive. The filaments are of sufficient resiliency to cause them to give and permit the extraction of the retaining member from the bookbinding when a sufficient pull is given the ribbon.

When not in use in a book, my improved bookmark is preferably combined with a protective carrying case composed of thin sheet material bilaterally or trilaterally folded into an open end envelope. A representation of a book may be printed on the front of the envelope and a slit cut therein adjacent to the top of the back of the illustration of the book. The retaining member is inserted

through this slit and the ribbon is wound around a leaf or leaves of the envelope which may be retained in folded position by a tongue cut from one leaf thereof and engaged in a complementary slot cut in another leaf.

The characteristics and advantages of my invention will more fully appear from the following description and the accompanying drawing in illustration of a preferred embodiment thereof.

In the drawing, Fig. 1 is a broken elevation of a detachable bookmark embodying my invention; Fig. 2 is a partly broken front elevation of a container with my improved bookmark housed therein in accordance with my invention; Fig. 3 is a fragmentary view of a modified form of container partly open; Fig. 4 is a fragmentary perspective view of a book with my bookmark inserted therein for use; and Fig. 5 is a fragmentary vertical sectional view through the back of the bookbinding showing the lower portion of the bookmark retainer with the filaments in engagement with the binding.

As illustrated in the drawing, a strip of sheet material 1 is folded so as to embrace between the laminations thereof the sheaf or layer of resilient filaments 2, such as natural or artificial horse-hair, fine spring wire, or the like. The laminations are secured to the filaments 2 and to one another by an adhesive 3, which also secures between the laminations a ribbon 4.

As illustrated in Fig. 2, a container for the bookmark is provided by a folder 5 bent along the crease 6 and having printed thereon an illustration 7 of a book with its back 8 and side 9 toward the spectator. A slit 10 is cut in the front leaf of the folder 5 at the top of the book back 8 and notches 11, 11' are formed in the bottom and front edge of the front leaf of the folder 5. A tongue 12 is hinged to the front leaf of the folder 5 and passes through a slit 13 in the back leaf 5' of the folder.

For merchandising and demonstration, the retaining member 1 is inserted in the slit 10 of the container so that the filaments 2 are housed between the front and back leaf of the folder 5, and the ribbon 4 is bent over the

front leaf of the folder 5, passes downwardly between the leaves of the folder, is engaged in the notch 11, bent upwardly over the front face of the folder and has its end secured in 5 the notch 11' with its free end housed between the folder leaves. By inserting the tongue 12 in the slit 13, the leaves of the folder are secured together.

As illustrated in Fig. 3, the front leaf 5 10 of the container may have a leaf hinged along each edge thereof. In this modification of the container the notch 11' may be omitted and the inturned leaf 5a notched to form a tongue 11a for receiving the folded end of 15 the ribbon. A tongue 12a is also cut in the inturned leaf 5a for insertion in a slit 13a formed in the leaf 5b, which overlaps the leaf 5a when the container is closed.

In the practical utilization of my improved 20 bookmark, the retainer formed by the body 1 and filaments 2 is pushed down between the back strip 14 of the binding and the back edges of the leaves 15 of a book 16. The 25 length of the filaments 2 is greater than the thickness of the book and consequently the filaments are bent, as shown in Fig. 5, and bear outwardly against the sides of the back strip 14 with their ends frictionally contacting therewith. The frictional engagement 30 firmly anchors the retaining member against accidental displacement, but when the ribbon 4 of the member 1 is firmly grasped and pulled, the filaments are bent and yield sufficiently to permit the removal of the retainer from the housing formed by the bookbinding. The ribbon is used in the usual 35 way as a guide for locating a desired place in a book.

Having described my invention I claim— 40

1. A detachable bookmark comprising a finder and a setaceous retainer.

2. A detachable bookmark comprising a finder and a retainer comprising resilient anchoring devices.

45 3. A detachable bookmark comprising a finder and a retainer having elastic filaments projecting laterally therefrom.

4. A detachable bookmark comprising a finder and a retainer bent over a layer of 50 setaceous members.

5. A detachable bookmark comprising laminated sheet material, setaceous members engaged between said laminations, and a ribbon engaged between said laminations.

55 6. In testimony whereof I have hereunto set my hand this 27th day of February, 1932.

WILLIAM T. DEMPSEY.
